F. R. HOYT,
MAGNETO ELECTRIC MACHINE,
APPLICATION FILED JUNE 14, 1915.

1,226,666.

Patented May 22, 1917.

Francis R. Hoyt INVENTOR
M. W. H. & CO. BY ATTORNEYS

UNITED STATES PATENT OFFICE.

FRANCIS R. HOYT, OF EAST ORANGE, NEW JERSEY, ASSIGNOR TO THE SIMMS MAGNETO CO., A CORPORATION OF NEW YORK.

MAGNETO-ELECTRIC MACHINE.

1,226,666.

Specification of Letters Patent. Patented May 22, 1917.

Application filed June 14, 1915. Serial No. 33,886.

To all whom it may concern:

Be it known that I, FRANCIS R. HOYT, a citizen of the United States, residing at East Orange, in the county of Essex and 5 State of New Jersey, have invented certain new and useful Improvements in Magneto-Electric Machines; and I do hereby declare the following to be a full, clear, and exact description of the invention, such as will enable others skilled in the art to which it 10 pertains to make and use the same.

My invention consists in the novel features hereinafter described, reference being had to the accompanying drawing which 15 illustrates, in part diagrammatically, an embodiment of the invention selected by me for purposes of illustration and the said invention is fully disclosed in the following description and claims.

20 The object of this invention is to provide a magneto electric machine the armature of which has two maximum potential or sparking positions in each half revolution thereof, which will be, preferably, one at full advance and one at full retard, in which the 25 armature cuts the greatest number of lines of magnetic force as compared with other positions, and which will provide these two sparking positions at low speed and also at high speed.

30 Referring to the said drawing:

Figure 1 is an elevation of so much of a magneto electric machine embodying my invention as is necessary for a clear understanding of the invention, and showing the 35 construction and relation of the magnet or magnets, the pole shoes and the armature core, the coils of the armature being indicated diagrammatically and the parts being shown in the sparking position at full advance.

40 Fig. 2 is a similar view of the pole shoes and armature coil shown in Fig. 1 with the armature in sparking position at full retard.

45 Fig. 3 is a detailed perspective view of one form of pole shoes detached which I conveniently employ in carrying out my invention.

50 Fig. 4 is a detailed perspective view of the armature core detached.

55 My present invention is an improvement upon the magneto electric machine shown and described in Letters Patent of the United States granted to William O. Ken-

nington, #1,039,543, dated September 24th, 1912, and has for its object an improvement in the construction of magneto electric machines of the kind therein shown.

In magneto electric machines, as generally constructed, the coils or windings of the armature cut the largest number of lines of magnetic force at one position only in each half revolution of the armature, at which time the current induced in said windings reaches its highest potential. Obviously the two positions of the armature in which the highest potential is reached in a complete revolution of the armature are diametrically opposite to each other, and the current induced when the armature is in one position is in the reverse direction to that induced when the armature is in the other position. In the use of magneto electric machines in connection with ignition systems for internal combustion engines and for other purposes in which a spark is required, it is customary to interrupt or break the circuit through the primary winding of the armature and by means of a secondary winding on the armature or by an induction coil to obtain a high tension current through the circuit including the spark gap and therefore it is customary to break the circuit through the primary winding of the armature at the instant or instants when the current induced in the primary winding is at its highest potential.

These positions of the armature are therefore called the sparking positions. It is also customary to advance and retard the instant of breaking the primary circuit in the cycle of revolution of the magneto armature which obviously results in breaking the primary circuit when the armature is in positions more or less remote from the true sparking position so that for example, if the interruption at full retard is more or less coincident with the true sparking position of the armature then the interruption at full advance will be more or less remote from the true sparking position and vice-versa.

In carrying out my present invention I provide the magneto magnet or magnets with pole shoes, each of which is provided at one end with an extended portion, extending around the armature in the direction of the rotation thereof, said extended portion being provided with a recess extending in a direction parallel to the axis of rotation of the

armature and forming at its inner edge a shoulder at the end of the grooved portion of the inner surface of the pole shoe, which I term for convenience of reference, the inner terminal shoulder while the outer edge of the said extension forms the external or outer terminal shoulder thereof, and in connection with pole shoes of this character I employ an armature core having each of its curved exterior surfaces provided with a groove extending parallel to the axis of rotation and so located that as the rear edge of one of said curved surfaces of the armature leaves the inner terminal shoulder of a pole shoe the said recess will lie beneath the exterior terminal shoulder and provide a greater gap than exists between the curved portions of the armature and the curved inner surface of the pole shoes.

In Fig. 1, for example, I have shown a magneto structure in which 1 represents the magnet or magnets, preferably permanent magnets of horse shoe form, and 2, 2, represent the pole shoes each of which is provided with a curved inner surface as at 3. Each pole shoe is provided at one end of said curved surface with an extension, 4, extending in the direction of the rotation of the armature around the same, and provided with a recess, 5, thus forming the inner terminal shoulder, 6, at the inner edge of said recess. The outer end of the extension provides the outer terminal shoulder, 7, which is located at the same distance from the axis of rotation of the armature as the curved portion 3 of the shoe, and I prefer also to cut off the corners of the extended portion, 4, as indicated at 8, as shown best in Fig. 3. 10 is the armature core which is provided in this instance with the primary winding, 11, and secondary winding, 12, indicated diagrammatically in Figs. 1 and 2. The core is provided with oppositely disposed curved portions, 13, concentric with the axis of rotation and therefore of necessity providing a uniform gap between them and the portion, 3, and the interior and exterior shoulders 6 and 7 of the pole shoes. Each of said curved portions, 13, is provided with a recess, 14, which extends in a direction parallel to the axis of rotation, and this recess, 14, is located adjacent to the rear or "following" edges or tips, 15, of said curved portions, having reference to the direction of rotation of the armature, the leading edges or tips of said curved portions being indicated at 16. The said recesses are so arranged that when the rear edges, 15, of the curved portions of the armature are opposite the inner terminal shoulders, 6, of the pole shoes, which will be the sparking position at full advance, the recesses, 14, will be beneath the exterior terminal shoulders, 7, of the pole shoes as clearly shown in Fig. 1, so that there will be a much greater gap between the exterior

shoulders, 7, and the recessed portions of the armature than the normal gap which exists between the other portions of the armature and the curved portions of the pole shoes and the terminal shoulders thereof.

Hence, any tendency of the magnetic flux to be diverted through the metal core of the armature is prevented and the, substantially, maximum lines of force are cut by the armature coils when the armature is in the position shown in Fig. 1 at full advance. Or in other words, each of said recesses, 14, is so located that at the time the rear edges or tips of the armature are leaving the advance spark portions, 6, of the pole shoes, the recesses, 14, are adjacent to the retard portions, 7, of the pole shoes and insure greater reluctance between the core and the extended ends of the pole shoes than between the core and the advance spark portions.

The armature also has a second sparking position at full retard which, as illustrated in Fig. 2, is at the point when the rear edges, 15, of the curved portions of the armature core leave the exterior terminal shoulder at the outer end of the extensions 4, of the pole shoe. In this position it will be seen that the coils of the armature cut substantially, the maximum lines of force and that the spark produced by the interruption of the circuit through the primary coil in either of these positions will be substantially equal in intensity at any given speed of revolution of the armature.

The armature therefore has two sparking positions in each half revolution at which a hot spark can be secured. It will be understood that the magneto construction herein shown and described is intended for use in the usual and well known manner in connection with a timer or adjustable periodic interrupter capable of being adjusted so that the spark can be advanced or retarded in the usual manner. Such apparatus however, is well known and as it forms no part of my invention it is not herein particularly shown or described.

It will be obvious that in running at slow speed the timer will be placed in the retarded position and that substantially as hot a spark is obtained as would be the case if the timer were in the advanced position. When running at high speed the timer will be ordinarily advanced and substantially as hot a spark will be obtained at high speed in either the retarded or advanced positions.

A magneto electric machine, to which my invention is applicable, is shown, for example, in Letters Patent of the United States No. 1,039,454, granted September 24th, 1912, in which it is shown associated with a periodic interrupter or mechanical circuit breaker, and timing lever as well as other features, but my invention is appli-

cable to other types of magneto electric machines as well.

I claim—

1. In a magneto electric machine, the combination with a magnet, of pole shoes therefor each having one extremity extended a greater distance in a direction around the armature than the other extremity, the inner face of each pole shoe being provided adjacent to the extended extremity thereof with a transversely extending recess and having an advance spark portion on one side of the recess and a retard spark portion on the other side of the recess on the extended extremity of the pole shoe, and a rotarily movable armature having a core provided with exterior curved surfaces each having a recess therein extending in a direction parallel to the axis of rotation of the armature, said recesses being so located that at the time the rear edges or tips of the armature are leaving the advance spark portions of the pole shoes the said recesses are adjacent to the retard portions of the pole shoe, and insure greater reluctance between the core and the extended ends of the pole shoes than between the core and the advance spark portions of the pole shoes.
2. In a magneto electric machine, the combination with a magnet, of pole shoes therefor each having one extremity extended a greater distance in a direction around the armature than the other extremity, the inner faces of each of said pole shoes being provided adjacent to the extended extremity thereof with separated retard spark portions and advance spark portions, and a rotarily movable armature having a core provided with separated exterior curved surfaces each having a recess therein extending in a direction parallel to the direction of the armature and located in advance of the rear edge or tip of said curved surface substantially equal to the distance between the advance spark and retard spark portions of the pole shoes, whereby when the rear tips of the curved portions of the armature core are leaving the advance spark portions of the pole shoes said recesses will be adjacent to the retard spark portions thereof and insure greater reluctance between the core and the pole shoes at such points, than between the rear tip and the advance spark portions.
3. In a magneto electric machine, the combination with a magnet, of pole shoes therefor each having an inner curved surface concentric with the axis of rotation of the armature and a portion at one end of the shoe extending a greater distance in the direction of rotation than the other end of the shoe, said pole shoes each having a retard spark portion at the extended end thereof at substantially the same distance from said axis as the curved portion, a recess extending parallel to said axis, and an advance spark portion at the inner edge of said recess, and a rotarily movable armature having its core provided with separated exterior curved surfaces concentric with the axis of rotation and each provided with a recess extending parallel to said axis, and located a distance in advance of the rear edge or tip of said curved portion substantially equal to the distance separating the advance spark portion and retard spark portion of the pole shoes, whereby when said rear edges or tips of the armature are leaving the advance spark portions of the pole shoes the said recesses are adjacent to the retard portions of the pole shoes, to insure greater reluctance between the core and said retard portions than between the rear edges or tips and the advance spark portions.

In testimony whereof I affix my signature.

FRANCIS R. HOYT.
